UNITED STATES PATENT OFFICE.

WALTER P. EVANS AND CHARLES W. CARR, OF MEADOW GROVE, NEBRASKA.

BALING-PRESS.

No. 866,637.

Specification of Letters Patent.

Patented Sept. 24, 1907.

Application filed June 3, 1907. Serial No. 376,995.

To all whom it may concern:

Be it known that we, WALTER P. EVANS and CHARLES W. CARR, citizens of the United States, residing at Meadow Grove, in the county of Madison and State 5 of Nebraska, have invented certain new and useful Improvements in Baling-Presses; and we do declare the following to be a full, clear, and exact description of the invention, such as will enable others skilled in the art to which it appertains to make and use the same.

10 This invention relates to baling presses, and more particularly to an automatic tier for the same; and has for its object to provide a device of this kind which can be applied to presses of different construction, and is adapted to be operated automatically by the action 15 of the plunger whenever the bale being formed has reached the desired length or dimension.

In the accompanying drawings, which illustrate the invention,—Figure 1 is a top plan view of a portion of a press embodying the invention; Fig. 2 is a side elevation of the needle; Fig. 3 is a similar view from the opposite side; Fig. 4 is a longitudinal sectional view of the same with a portion of the press; Fig. 5 is a transverse sectional view taken near the rear end of the needle and with the looper shown in elevated position; 20 Fig. 6 is a broken side elevation of the looper detached; Fig. 7 is a broken enlarged side elevation of the tripping mechanism.

Referring more particularly to the drawings, 1 indicates the press, which may be of any desired construction, having an ordinary baling chamber 2, feed chamber 3, and reciprocatory plunger 4.

The sides of the press are provided with openings 5 at a point substantially between the feed chamber and the baling chamber, one above the other, for the passage 35 of the needles 6 for the purpose of tying the binding wire around the bale, two wires being generally used for such purpose.

The needles are exact duplicates of each other, and therefore, a description of one will apply to both. In 40 their normal or inoperative positions the needles are supported on tracks 7, which extend laterally from one side of the press at the lower portions of the openings 5. The track is preferably provided with facing recesses 8, which may be formed by means of substantially U-shaped metal bars within which the needles are adapted 45 to be reciprocated.

Each needle consists of two parallel bars 9, which are preferably substantially inverted T-shape in cross section, spaced apart by cross pieces 10, with the outer 50 portion 11 of each head of the T fitting in the recesses 8. The upper edge of each bar is formed or provided with a flange 12, which overhangs the inner portion of the head of the T and thereby forms a trackway for the knotter or mechanism for joining the ends of the wires 55 and twisting them together. The knotter consists of a base 13, which has its sides provided with depending

walls 14, which fit in between the flange 12 and the inner portion of the head of the T bar.

Journalized upon the under side of the base is a gear wheel 15, which is adapted to engage with a rack 16, 60 which is secured at its ends to two of the cross pieces 10 at one side of the center of the track 7. The upper face of the wheel 15 is beveled and provided with gear teeth 17, which are adapted to engage with a bevel pinion 18 journaled at one side of two upwardly extending walls 19.

The shaft of the pinion between said walls is provided with a pinion 20, which engages with two other pinions 21, one upon each side and near the upper edge of the walls 19. The pinions 21 are each slotted radially, as shown at 22, which slots are adapted to register with slots 23 in the walls 19. Two hooks 24 are pivotally mounted upon one of the walls 19, each having its upper end curved, as shown at 25, which is adapted to normally extend across one of the slots 23, 75 whereby the wires may be inserted into the slots by forcing the hooks back out of the way against the tension of a spring 26, after which, it will be impossible for the wires to be removed, on account of the hooks 24.

Two standards 27 and 28 are located at a short distance from the rear wall 19, and one of them is provided with a perforation 29, through which the wire is passed through to the slot 22 in one of the pinions 21. Pivotally mounted upon the standards are two knife blades 30, which are adapted to be forced against the sides of 80 the standards by means of a lever 31, that is pivoted at one end to the rear wall 19, and has its intermediate portion slotted for engaging with the heels or inner ends of the knife blades 30, when the free end of the lever is raised. The free end of the lever has its under 90 surface curved, as shown at 32, whereby it is adapted to engage with a projection 33 upon one of the cross pieces 10, the projection being substantially triangular and having its front and rear walls inclined for the purpose of engaging with the lever 31 and swinging it upward, for the purpose of cutting the baling wire, by means of the blades 30. The weight of the lever is such that its free end normally hangs down far enough to keep the blades away from the standards, for the insertion of the wires. 95

Journalized transversely of the knotter frame or base 13 is a shaft 34, one end of which is provided with a double mutilated gear wheel 35, and the other end is provided with a cam 36, having a flat face 37, whereby the shaft may be locked against rotation. The intermediate portion of the shaft is provided with a bale-like looper 38. The looper is adapted to lie substantially flat or even with the knotter frame when in its inoperative position, with a standard 39 projecting upwardly from the base 13 between the sides or legs 40 of the 105 looper; and it is adapted to have its free end swung over the walls 19 and adjacent to the standards 27 and 110

28, the legs being curved, as at 41 for this purpose. The legs are provided with notches or recesses 42, which are adapted to register with the slots 23 and with the open knife blades 30, the notches nearest the shaft 34 being 5 formed between diverging prongs 43. The free end of the looper is preferably provided with a grooved wheel or pulley 44, over which the wire is adapted to pass from the notches 42 upon one leg to those upon the other leg.

10 The shaft is adapted to be rotated by means of two short racks 45 and 46, one of which is located at one side of the press in position for engaging with the gear teeth 47 of the wheel 35 for the purpose of swinging the looper from its normal position to form loops in the wire; and 15 the other rack is located upon the side of the needle frame in position for engaging with the teeth 48 for returning the looper to its normal position while the knot is being tied.

The standard 39 is provided with a horn 49, which is 20 recessed at its base, as shown at 50, and a knife blade 51 is pivotally secured to the standard below the said recess in position for having its knife edge forced up past said recess when its free end engages with an inclined projection 52 upon the cross bar 10 at the forward end of the needle, and thereby sever the wire that 25 has been drawn into said recess.

Journalized lengthwise of the knotter frame upon one side in brackets 53 is a shaft 54, which has two oppositely extending horn-like projections 55 at one end, 30 and a lateral bend 56 at the other for rotating the shaft when said bend is forced into engagement with an inclined plate or blade 57 secured to one side of the press. A hook-like projection 58 projects laterally from the intermediate portion of the shaft 54 substantially in 35 alignment with the recess 50, in the horn 49 and coacts with a bracket 59 secured to the side of the baler on the other side of the knotter for the purpose of assisting in forming the loops in the wires when the looper is swung from its forward or normal position to the rear.

40 In the drawings the projection 58 is shown as being secured to the shaft 54 by means of a collar 60, which has a portion of its rear end formed into a cam 61 for engaging with the flat portion 37 of the cam 36 and thereby locking the shaft 34 against rotation.

45 A spring tongue 62 is secured to one side of the press and has its free end inclined, as shown at 63 and provided with two shoulders 64 and 65. One of the shoulders, as 64, is adapted to engage with a loop or projection 66 upon the bottom of the base 13 and hold the 50 knotter against return movement when the knot is being tied, and the other shoulder is adapted to be engaged by a projection 67 upon the forward cross bar 10 to force the shoulder 64 down out of engagement with the loop 66 after the knot has been tied, and thereby 55 permit of the return of the needle. A guard returning wall 68 is secured at its ends to the inclined blade 57 for the purpose of engaging with the lateral bend 56 of the shaft 54 for the purpose of returning said shaft to its normal position, thereby locking the looper in its inoperative 60 position, and also throwing one of the wires out of one of the pinions 22, by means of one of the horns 55 when the needle is being withdrawn.

Two spools of wire 69 and 70 are mounted upon opposite sides of the press in any desired manner, and the 65 wire 71 from one of them is adapted to be passed through

the perforation 29 in the standard 27, and the wire 72 from the other spool is adapted to be passed through a perforation or recess 73 in the outer end of the bracket 59, and the ends of said wires are provided with interlocking loops 74, whereby the two wires are caused to 70 extend across the press in position for being engaged by the material and carried forward with the end of the bale, as it is being gradually formed by the reciprocation of the plunger.

The needles are adapted to be reciprocated in any 75 desired manner, one of which is shown in the drawings, and consists of a rock shaft 75, which is journaled vertically upon one side of the press, and is provided with two arms 76, the free ends of which are adapted to be connected with the respective needles by means of 80 links 77. The rock shaft is adapted to be actuated in any desired manner, as by means of an arm 78, which extends across the pitman for the plunger and is adapted to be engaged by two shoulders 79 and 80, formed thereon, preferably near one edge, as in a flange 81. 85

The arm 78 is adapted to normally enter the recess between the shoulders 79 and 80, as by gravity or spring pressure, but is normally held out of engagement with the plunger by means of a block 82, which is provided with a shoulder 83. An inclined wall or surface 84 is 90 located near the shoulders 79 and 80 when the plunger is at the rear limit of its stroke, with which the arm 78 is adapted to engage, and thereby be raised out of engagement with one of the shoulders, as 79, but not out of position for being engaged with the other shoulder 80, 95 which is higher than the shoulder 79.

The block 82 is adapted to be drawn out from under the arm 78 by means of a cord 85, which is adapted to be wound around upon the hub of a toothed wheel 86. The wheel 86 is journaled in one end of a lever 87, which is 100 pivoted in a bracket 88 upon one side of the press. The other end of said lever is adapted to be engaged by a pin or projection 89 upon one of the needles 6, whereby the wheel 86 is moved out of engagement with the bale, which permits a coiled spring 90 to return the block 82 105 to its normal position. While the arm 78 is resting upon the inclined wall 84, the lever 87 is returned to its normal position with the wheel 86 in engagement with the bale of hay by means of a coiled spring 91.

In operating a press as above described, the needle is 110 withdrawn to its outer limit, and the knotter placed upon the forward end of the needle, preferably by causing it to engage with a suitable stop secured to the side of the press. The wire 71 is then passed through the perforation 29 and the slots 22 and 23 and securely fastened to the end of the wire 72, which has been passed through the perforation in the end of the bracket 59. The material is then fed into the press in the ordinary manner, which is carried forward against the two wires by the plunger in the ordinary manner, which will 115 gradually carry the wires down into the baling chamber in front of the bale, thereby drawing the wire equally from the spools upon the opposite sides of the press. As the bale moves forward the wheel 86 gradually winds up the cord 85 and pulls the block 82 from under the 120 arm 78 until the arm finally drops off the shoulder on the block into the recess between the shoulders 79 and 80 on the plunger. As soon as the plunger starts on its rebound, the shoulder 79 engages with the arm 78 and carries it to the rear, thereby rocking the shaft 75 and caus- 125 130

ing the arms 76 and links 77 to force the needle across the press to the rear of the finished bale. When the needle starts forward the strain of the wire against the side of the bale will hold the knotter stationary while 5 the needle moves forward the length of the rack 16, or until it reaches the rear end of the needle head. The knotter and needle are then carried forward with the wire 71 passing through a perforation in the rear end of an arm 92, which is secured to the knotter, and from 10 there it passes through the perforation 29 to the twister head or pinion 21 at that end of the walls 19 and around the grooved wheel 44 with one portion of the wire adjacent to the bale lying between the horns 55. As the needle moves forward it passes under the portion of the 15 wire 72, which passes down the opposite side of the bale, and thereby draws said wire into the recess 50 under the horn-like projection 49, and also in front of the projection 55, which has been turned up by that time by the engagement of the lateral bend 56 with the inclined 20 plate or holder 57. By the time the needle has reached this point, the shaft 54 has been rotated far enough to unlock the shaft 34 and also to cause the gear teeth 47 on the wheel 35 to engage with the rack 45, and thereby rotate the shaft 34 and swing the looper 38 to the rear, 25 folding the two portions of the wire 71 over the wire 72 and also bending the wire 72 back toward the slotted pinion or twister heads 21. The rotation of the shaft 54 causes one of the horns 55 to carry the wire above the slots 22 and 23 at that end of the walls 19. As the looper 30 is carried backward by the engagement of the teeth 47 with the rack 45, the notches 42 formed therein will engage with said wires, and force them down into the slots 22 and 23 past the hooks 24 with the portion of the wire upon each side of the looper between the prongs 43 and 35 the notches 42 near the wheel 44 in between the knife blades 30 and the standards 27 and 28. By the time the parts of the knotter have reached the position as above described, the needle has reached the limit of its forward movement, and has caused the loop 66 to engage 40 with the shoulder 64 and thereby hold the knotter against return movement with the needle. As soon as the needle starts on its return movement the lever 31 is lifted by the projection 33, which causes the blades 30 to cut off the portion of the wire that extends around the 45 grooved wheel 44. By the time this has been done, the gear teeth 48 engage with the rack 46 and return the looper 38 to its normal position. The further return movement of the needle, while the knotter is thus held stationary, causes the projection 52 to pass under the 50 free end of the knife blade 51 and force it up against the horn 49 and sever the portion of the wire 72, which has been drawn transversely across the needle from the bracket 59 and has been connected with the portion of the wire 71, which has been placed across the rear end 55 of the bale. As soon as this has been done, the projection 67 engages with the shoulder 65 on the spring 62 and forces the shoulder 64 down out of engagement with the loop 66. The further movement to the rear of the needle will carry the knotter mechanism with it, with 60 the wire 71 passing through the perforation in the arm 92 and through the perforation 29 and pinion 21. By providing the arm 92, there is always a sufficient amount of wire 71 drawn from the reel during the slower movements of the press to afford enough slack that when the 65 needle is carried across the baling chamber its rapid

movement caused by the rebound of the plunger will prevent the liability of breaking the wire. At the same time that the needles reach the limit of their forward movement, the pin 89 upon one of them engages with the lever 87 and moves it so as to release the toothed 70 wheel 86 from the bale, and thereby permits the coiled spring 90 to draw the block 82 under the arm 78, so as to hold the arm out of the path of the shoulder 79, and thereby permit the free reciprocation of the plunger after the shoulder 80 has carried the arm 78 forward to 75 withdraw the needles as above described.

From the foregoing description, it will be evident that the needle and knot-tying mechanism can be easily applied to any ordinary press, and thereby automatically tie each bale as soon as it is formed. In this 80 manner, the operation of baling can be continuous, and the size of the bale can be changed or varied at any time by lengthening the cord 85 or by manually withdrawing the wheel 86 from engagement with the bale and unwinding or winding up a portion of the cord, as 85 the case may be, to withdraw the block from under the arm of the rock shaft, sooner or later, as it is desired to have the length of the bale greater or less.

Having described our invention, we claim:—

1. In an automatic binder for hay presses, a needle 90 frame provided with means for reciprocally moving it across the press, a knotter reciprocally mounted thereon, and means for automatically actuating the knotter as it is being moved upon said frame.

2. In an automatic binder for hay presses, a needle 95 frame provided with means for reciprocally moving it across the press, of a knotter reciprocally mounted thereon, and means for automatically forming two interlocking loops when the knotter is reciprocated.

3. In an automatic binder for hay presses, a needle 100 frame, a knotter reciprocally mounted thereon provided with a pivoted looper, and means for automatically forming two sets of interlocking loops when the knotter is reciprocated.

4. In an automatic binder for hay presses, a needle 105 frame, a knotter reciprocally mounted thereon, a bale-like looper, and twister heads for automatically forming two sets of interlocking loops.

5. In an automatic binder for hay presses, a needle 110 frame, a knotter reciprocally mounted thereon and provided with a shaft, a bale-like looper secured to the shaft and provided with a grooved wheel at its free ends, means for rotating said looper through a substantially semi-circle, twister heads for automatically forming two sets of interlocking loops, and means for severing the wire 115 between said loops.

6. In an automatic binder for hay presses, a needle 120 frame, a knotter reciprocally mounted thereon, a shaft journaled on the base of the knotter and provided with mutilated gear wheels at one end and a shouldered cam at the other, a bale-like looper secured, at its ends to said shaft and provided with a wheel at its free end, racks for engaging with said gear wheels and a lock for engaging with said cam, rotary twister heads for automatically forming two sets of interlocking loops, and means for 125 severing the wires between said loops.

7. In an automatic binder for hay presses, a needle 130 frame provided with a rack, a knotter reciprocally mounted on said frame and provided with a gear wheel for engaging with said rack, radially slotted twister heads adapted to be actuated by said gear wheel, a looper for carrying wires into said heads, means for automatically forming two sets of interlocking loops, and means for severing the wires between said loops.

8. In an automatic binder for hay presses, a needle 135 frame provided with a longitudinally disposed rack, a knotter reciprocally mounted on said frame and provided with a gear wheel in engagement with said rack, slotted walls on the base of the knotter, a shaft and two slotted

- twister heads mounted in said walls, two pinions on said shaft, one of which engages with the gear wheel and the other with said slotted pinions, a swinging looper for forcing the wires into said slots, means for automatically forming two sets of interlocking loops, and means for severing the wire between said loops. 50
5. In an automatic binder for hay presses, a needle frame provided with a projection at each end, a looper reciprocally mounted upon said frame and provided with 5 55
- 10 knives adapted to be actuated by said projections, twister heads, a looper for carrying wires thereinto and into engagement with said knives, and means for rotating the twister heads to form two sets of interlocking loops after the wire has been severed by a portion of said 15 knives and before the wire is severed by the other knife.
10. In an automatic binder for hay presses, a needle frame, a looper reciprocally mounted thereon provided with three standards and twister heads therebetween, a knife blade pivotally secured to each standard, a lever 20 for actuating two of said blades, a looper for placing wires in said heads, and projections for actuating said knives. 65
11. In an automatic binder for hay presses, a needle frame, a knotter reciprocally mounted thereon provided with three standards and slotted wheels therebetween, one of the standards being provided with a perforation, another one with a recessed horn, and each of them provided with a knife blade pivotally secured thereto, twister heads and spring-pressed hooks for the slots in said walls, 25 a bale-like looper pivotally mounted upon the base of the knotter and having its legs provided with notches for registering with the slots in said walls, and means for rotating said twister heads, moving the looper and actuating the knife blades during the reciprocation of said 30 knotter. 70
12. In an automatic binder for hay presses, a needle frame, a knotter reciprocally mounted thereon provided with twister heads, a swinging bale-like looper, a flat faced cam, a shaft journaled at one side of the knotter 40 and provided with means for engaging with said flat face, and thereby locking the looper against movement, and means for automatically rocking said shaft when the knotter is reciprocated. 75
13. In an automatic binder for hay presses, a press 45 having its sides provided with openings, tracks adjacent to said openings, a bracket, a rack and an inclined plate adjacent to the openings upon one side, a needle frame reciprocally mounted upon the track at the other side of the frame and provided with a rack, a knotter recipro- 80
- cally mounted on said frame and provided with slotted 50
- twister heads, two shafts at right angles to each other, one end of one of the shafts being provided with mutilated gear wheels for engaging with said racks, horns on one end of the other shaft for carrying a wire to and from one of the twister heads and having its other end 55 bent laterally for engaging with said inclined plate, and means for actuating the twister heads when the knotter is reciprocated.
14. In an automatic binder for hay presses, a press having its walls provided with openings, recessed tracks 60 adjacent to said openings, a shouldered spring between the tracks at one side of the press, a flanged needle frame for engaging with said tracks and provided with a projection for engaging with one of the hooks of said spring, a knotter reciprocally mounted on said frame, and 65 provided with a looper for engaging with the other shoulder of said spring, and means for forming two sets of interlocking loops when said knotter is reciprocated.
15. In an automatic binder for hay presses, a press having its walls provided with openings, tracks adjacent 70 to said openings, needles reciprocally mounted on said tracks, a rock shaft journaled at one side of the press and provided with means for actuating the needles and being actuated by the plunger, a longitudinally movable member for controlling said means, a toothed wheel for 75 engaging with the side of a bale, and a cord from said member to said wheel for automatically permitting said means to be engaged by the plunger when a bale has been completed. 80
16. In an automatic binder for hay presses, a press, reciprocatory needles therefor, each provided with means for automatically binding a bale, means for reciprocally actuating the needles by means of the plunger, a lever pivotally mounted at one side of the press, one end of which is adapted to be engaged by one of said needles 85 when it is moved across the press, a toothed wheel pivotally mounted in the other end of said lever in position for being moved into and out of engagement with a bale, and means connected with said wheel for controlling the actuating means between the plunger and the needles. 90
- In testimony whereof we have hereunto set our hand in presence of two subscribing witnesses.
